(57) **CLAIM**

The ornamental design for a connector, as shown and described.

DESCRIPTION

FIG. 1 is a right, front, and top perspective view of a connector embodying our new design.

FIG. 2 is a left, front, and top perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a cross-sectional view thereof taken along 9-9 in FIG. 5; and,

FIG. 10 is a cross-sectional view thereof taken along line 10-10 in FIG. 5.

The broken lines in the figures show portions of the connector that form no part of the claimed design.

1 Claim, 10 Drawing Sheets
